UNITED STATES PATENT OFFICE.

JOHN W. BROWN, OF WASHINGTON, DISTRICT OF COLUMBIA.

PAN-LIFTER.

1,123,988.

Specification of Letters Patent.

Patented Jan. 5, 1915.

Application filed February 10, 1914. Serial No. 817,820.

To all whom it may concern:

Be it known that I, JOHN W. BROWN, a citizen of the United States, residing at Washington, District of Columbia, have invented certain new and useful Improvements in Pan-Lifters, of which the following is a specification.

The present invention relates to improvements in pan lifters, and is designed especially for use by cooks in handling pie pans in an oven or other places.

The primary object of the invention is to provide a device which is simple in construction, comparatively inexpensive in cost, and yet withal efficient and desirable for performing the functions required of it.

The invention resides in the novel combination of features of the device as will be hereinafter pointed out.

20. In the accompanying drawings I have illustrated one complete example of the physical embodiment of my invention constructed according to the best mode I have so far devised for the practical application 25 of the principles of my invention.

Figure 1 is a perspective view of a pan lifter according to my invention. Fig. 2 is a front view in elevation showing a pie pan held in the lifter. Fig. 3 is a detail 30 sectional view showing the manner of securing the arms of the lifter to the handle.

Broadly speaking, the lifter is made up of 35 three pieces, the two side arms 1 and 2 and the handle 3, but these parts are fastened together rigidly so that they practically 40 form an integer. The arms 1 and 2 are made up of spring or elastic metallic wire and are curved or circular in shape to conform to the circular outline of a pan generally used for baking pies. Each arm is 45 provided with two bars 4 and 5 which are furnished by bending the wire upon itself to form a return bend and the upright post 6 is thus formed. This post is offset 50 exteriorly from the circular arms so that the upper bar 4, when the device is grasping a pan, is located within the circular outline of the pan at the top, and the lower arm 3 directly under the upper arm is in position 55 to engage the inclined wall 7 of the pan 8. In this manner the offset posts engage the flange 9 of the pan and the lower arms 5 support the pan at its inclined side walls 7. The rear posts 10, 10 which are provided 60 by extending the ends upwardly and turning

them over the upper bars 4 perform the same function as the front posts, and are similarly offset.

Each bar 4 is bent to form a leg 11 and this bend provides a foot 12, the bar and leg being in planes at right angles to each other, but the leg is again bent at 13 and the wire is then continued at right angles to the leg 11 and parallel with the plane of the bar 4 to form a shank 14. At the ends 60 of these shanks are provided with a pair of integral barbs as 15, struck from the side thereof and these barbs are adapted to be pressed into the metal of sleeves 16, 17 which are formed integral with the flat band or 65 strip 18 which comprises two bends 19 19 and the inverted intermediate bend 20. These sleeves and band form the handle 70 of the device which is of spring or elastic or resilient metal and normally tends to 75 hold the side arms together as in Fig. 1.

The sleeves are pressed and rolled about the shanks while the two metals are heated and as the sleeve is turned over the shank the barbs 15 of the shank are caused to engage the sleeve to provide a tight joint at 80 all times. Even though the sleeve should become loosened on the shank, the barbs will prevent the shank from rotating within the 85 sleeve, and thus a rigid relationship is assured at all times between the shank and sleeve.

When at rest the implement is supported 90 on a level surface by its handle and the bend at the lower bar 5 and post 10, and in this position is readily grasped by the handle and sleeves. The loops 19 provide a broad contact for the palm of the hand and the two sleeves and shanks are grasped by the thumb and first finger. The resiliency of 95 the device is present in the intermediate bend 20 and it will be noted that the band at this point is narrower than in the loops or bends 19 to render the metal more flexible. The implement may be expanded as the 100 arms are passed about a pan, or it may be expanded by hand, but in either event the arms are passed about the pie pan and clasped thereabout by pressure upon the handle and sleeves so that the pan may be 105 moved as desired. In unclasping the arms they are spread apart and the implement withdrawn whereupon it resumes its normal 110 position due to its resiliency.

In baking pies in an oven, the inner pies

or those located farthest from the opening of the oven usually bake more rapidly than those nearer the door and it is frequently necessary to change the innermost pies to the position of the outermost ones. For this purpose the implement is especially useful for the reason that the legs 11 lift the handle above the top of a pie, so that with the handle grasped in the hand the user may 10 reach over one pie and clasp another pie in rear of the first. Then by lifting the innermost pie and withdrawing it over the first pie the first or outermost pie may be pushed into the place formerly occupied by the pie held by the implement. In this manner 15 the position of the pies may be changed in order that they may be subjected to the same temperatures of heat.

What I claim is:—

A pan lifter formed of curved gripping 20 jaws, an upstanding leg on each jaw and a horizontally extending shank projecting from each leg, combined with a sleeve permanently united with and embracing each shank, a flat band of resilient metal formed 25 integral with the sleeves and fashioned with a pair of loops to form a broad base, and said band formed with a spring bend between the loops.

In testimony whereof I affix my signature 30 in presence of two witnesses.

JOHN W. BROWN.
